FIG. 1

FIG. 2

FIG. 1 is a front perspective view of a cuff link backing showing our new design;

FIG. 2 is a rear perspective view thereof, a conventional cuff link plate being shown in broken lines for illustrative purposes.

The dominant features of our design for a cuff link backing reside in the full line portions of the drawing and consists of a pivot set between parallel bars which pass through a circular ring and continue terminating at a perpendicular weld ring spaced a set distance from the circular ring, all as shown.

We claim:

The ornamental design for a cuff link backing, substantially as shown and described.
